INVENTOR.

UNITED STATES PATENT OFFICE.

WILLIAM L. WEATHERLY, OF PHILADELPHIA, PENNSYLVANIA, ASSIGNOR
TO GEO. P. IDE, BRUCE & CO., OF TROY, NEW YORK.

STANDING COLLAR FOR FEMALE WEAR.

SPECIFICATION forming part of Letters Patent No. 278,758, dated June 5, 1883.

Application filed March 31, 1883. (No model.)

To all whom it may concern:

Be it known that I, WILLIAM L. WEATHERLY, a citizen of the United States, residing in the city of Philadelphia, in the State of Pennsylvania, have invented certain new and useful Improvements in Collars for Ladies and Children, of which the following is a specification, reference being had to the accompanying drawing.

10 My invention relates to improvements in ladies' and children's standing collars, which can be adjusted at the ends in front of and about the neck of the wearer by a cord or ribbon; and a principal object of my improvements is to provide cheap and simple means whereby an adjusting ribbon or cord can be neatly displayed in tasty form, both at the front ends and at one side of the collar, and whereby is avoided all necessity of having the 15 bowed or flowing ends of the cord or ribbon directly under or close to the chin of the person, where such ends would be most liable to annoy the wearer and to become most quickly soiled. That object is accomplished in the 20 collar represented in the aforesaid drawing by having through the standing upper portion of the collar three holes, two of which are in the two end parts and one in one side part, as shown at B B' and C, said three holes being 25 arranged and adapted to receive a cord or ribbon, as shown at C, whereby the collar can be adjusted to stand and fit easily and nicely around and upon the neck of the wearer. Preferably the cord or ribbon is inserted so as to 30 be displayed in front of the two end parts between the two end holes, as shown in said

drawing, and extended inward through those two holes, and thence in a double stretch along the inner surface of the collar to and outward through the said side hole, where the two end 40 portions of the cord or ribbon are drawn out to the proper degree to cause the collar to stand and fit nicely and easily around and upon the neck of the person, and there tied or secured together on the outside of the collar in 45 a bow or with flowing ends, as indicated in the drawing, or in any way to suit the fancy or taste of the wearer.

I do not claim a collar having holes through its two end parts, nor such a collar having a 50 necktie extending through such holes and secured therein.

What I claim as my invention is—

1. A collar having through its standing upper portion two holes in the two end parts and a 55 hole in one side part, all arranged and adapted to receive an adjusting cord or ribbon, as described.

2. A collar having through its standing upper portion two holes in the two end parts, a 60 hole in one side part, and a cord or ribbon extending in front of the two end parts between the two end holes, through the latter holes, and thence in a double stretch to and through the side hole, and there secured on the outer surface of the side of the collar, as set forth.

In testimony whereof I hereunto set my hand this 21st day of March, 1883.

W. L. WEATHERLY. [L. S.]
